UNITED STATES PATENT OFFICE.

LOUIS SANDERS, OF NEW YORK, N. Y.

DESIGN FOR A GARMENT-REGULATING ATTACHMENT FOR BELTS.

SPECIFICATION forming part of Design No. 32,840, dated June 12, 1900.

Application filed May 16, 1900. Serial No. 16,931. Term of patent 7 years.

To all whom it may concern:

Be it known that I, LOUIS SANDERS, a citizen of the United States, and a resident of the city of New York, borough of Brooklyn, in the county of Kings and State of New York, have invented and produced a new and original Design for a Garment-Regulating Attachment for Belts, of which the following is a specification, reference being had to the accompanying drawing, forming a part thereof, in which is represented a perspective view of a garment-regulating attachment for belts embodying the features of my design.

The design consists in a plate wherein the formation of the body includes a lower transverse section and upright sections connecting with the end portions of the transverse section, together with a corresponding flange formed at the bottom of the transverse section

of the body. The flanges extend from the same side of the body at an angle thereto.

A detail feature of the design consists in the formation of the flanges, the upper flanges having a downward and the lower flange an upward curvature.

Having thus described my invention, I claim as new and desire to secure by Letters Patent—

The design for a garment-regulating attachment for belts herein shown and described.

In testimony whereof I have signed my name to this specification in the presence of two subscribing witnesses.

LOUIS SANDERS.

Witnesses:

J. FRED. ACKER,
JNO. M. RITTER.
